UNITED STATES PATENT OFFICE.

MAX MAAG, OF ZURICH, SWITZERLAND.

ADJUSTING DEVICE FOR GRINDING-WHEELS.

1,228,798.

Specification of Letters Patent. Patented June 5, 1917.

Application filed July 26, 1916. Serial No. 111,425.

To all whom it may concern:

Be it known that I, MAX MAAG, a citizen of the Republic of Switzerland, residing at Hardstrasse 219, Zurich, Switzerland, have 5 invented certain new and useful Improvements in Adjusting Devices for Grinding-Wheels; and I do hereby declare the following to be a full, clear, and exact description of the invention, such as will enable others 10 skilled in the art to which it appertains to make and use the same, reference being had to the accompanying drawings, and to letters or figures of reference marked thereon, which form a part of this specification.

15 This invention relates to a mechanism for automatically adjusting grinding wheels an amount corresponding to their wear, and for automatically bringing such wheels into the proper position relatively to the blank. The 20 mechanism, constituting the present invention, is adapted to be used in a great many cases and its action is more accurate than any prior mechanism for the same purpose, of which I am aware.

25 According to this invention, the surface of the blank to be ground, or the working surface of the grinding wheel, and in some cases both these surfaces, are controlled by a 30 feeler lever, which actuates devices connected to electric circuits. These devices are adapted to close or open said electric circuits, which act in such a manner upon electromagnetic coupling members of devices for adjusting the grinding wheels, or in some cases 35 upon the blank, that controlling an adjustment of the grinding wheel, or a movement thereof into the proper position is effected by the position of the controlling surface.

40 This invention will now be more particularly described with reference to the accompanying drawings, which illustrate several constructional examples of the invention.

In these drawings:—

45 Figure 1 is a perspective view showing some parts in section of one embodiment of the invention,

Fig. 2 is a similar view illustrating an embodiment of the invention, in which the feeler member bears upon the working surface of the grinding wheel;

50 Fig. 3 is a perspective view of a third construction according to this invention embodying in part some features of the construction shown in Fig. 1 and in part some 55 features of the construction shown in Fig. 2, and

Fig. 4 illustrates an arrangement according to this invention adapted to be used in connection with machines grinding both when the table carrying the blank is moved 60 in one direction and when it is moved in the opposite direction.

In carrying the invention into effect and referring to Fig. 1, I provide on a main standard 1 of a grinding machine, for instance a surface grinding machine, a vertical slide 7 adapted to be moved in vertical direction by means of a hand wheel 2, bevel gearing 3, 4, screw spindle 5 and nut 6. In the slide 7 is mounted a constantly revolving 70 shaft 8 driven by worm gearing 9, 10, and a belt pulley 11. An electromagnet 12 is rigidly mounted on the shaft 8, and a sleeve 13, provided at its lower end with ratchet-teeth 14 and carrying at its upper end a pinion is 75 loosely mounted thereon. Pinion 15 meshes with a second gear 16, which is rigidly mounted on a screw spindle 17. The latter engages with a nut 18 of the bracket 19, in which is journaled the grinding wheel spindle 20, carrying the grinding wheel 21. This wheel grinds the blank 23, held on the table 22, which is reciprocated on ways as usual.

24 denotes a feeler lever, which is pivotally connected at 25 to the slide 7. The right hand end of this feeler lever carries a small disk 26, which is constantly pressed against the ground surface 28 of the blank 23 by a strong spring 27. The left hand end of lever 24 acts upon the right hand end of a contact lever 29 pivotally connected at 30 to the slide 7. The left hand end of this lever 29 carries a contact piece 31 and a weak spring 32 tends to pull said contact constantly toward a small contact plate 33 fixed to the slide 7. The contact piece 33 is electrically connected to one pole of a source of electric current 34, the other pole of which is connected to the contact piece 100 by means of a connection, comprising two contact rings 35, mounted on the shaft 8, and the windings of the electromagnet 12.

It will be seen, that when the ground surface 28 of the blank 23 is in a sufficiently 105 high position, the contact piece 31 comes into contact with the small plate 33. At this time the electric circuit is closed and the electro-magnet 12 energized, so that it attracts an iron lever 36 arranged opposite 110 its pole 36 and pivoted on a pin 37, fixed to the body of the electromagnet 12, the front

end 39 of this lever 38 being thereby caused to engage with the teeth 14 of the sleeve 13. Owing to the fact that the electromagnet 12 is, as stated, rigidly connected to the shaft 8, the revolving movement of the latter is transmitted to the sleeve 13, the spur gearing 15, 16 and the screw spindle 17 as soon as the lever 38 engages with the teeth 14 of said sleeve 13, so that the bracket 19, carrying the grinding wheel 21, is gradually lowered. Owing to this, the grinding action of the wheel 21 upon the blank 23 is immediately increased and the ground surface 28 comes to lie to a certain amount lower down, this amount corresponding to the sinking of the grinding wheel. Further, as the action of the strong spring 27 overcomes the action of the weak spring 32, the small disk 26 of the feeler lever 24 is also moved downward to a corresponding amount, while on the other hand the contact piece 31 is moved away from the contact plate 33. The electric current flowing through the windings of the electromagnet 12 is now interrupted and the end 39 of lever 38, acted upon by the spring 34, is caused to disengage the teeth 14 of the sleeve 13. Hence, the revolving movement of the sleeve 13 and the downward movement of the grinding wheel 21 are arrested. This occurs at the time, at which the contact between the pieces 31 and 33 is interrupted, that is, at a determinate distance of the ground surface 28 from the lower edge of the slide 7.

Should it be necessary to grind off a further amount of the blank, the slide 7 is lowered to a corresponding amount by means of hand wheel 2 and the screw spindle 5, while the blank 23 is on the right hand side out of reach of the grinding wheel 21. Upon a downward movement of the slide 7, the support 19 and the grinding wheel 21 are also caused to move in the same direction. During the immediately following movement of the table 22 toward the left, the blank 23 is ground off to an amount, which corresponds to said downward movement of the slide 7, so that the distance of the surface 28, just acted upon by the wheel 21, from the lower edge of the slide 7, is again exactly the same as before the grinding. The grinding of the blank causes, however, a continual wear of the grinding wheel, so that the parts of the ground surface 28, lying farther to the right are left progressively higher than the left hand end of said surface, which has been acted upon by the grinding wheel at the beginning of the table movement. The smallest elevation of the ground surface has, however, the effect to lift the feeler disk 26 to an amount corresponding to said elevation, so that the contact piece 31 comes then again into contact with the contact plate 33, the hereinbefore described working cycle being re-

peated and a lowering, that is, an adjustment of the grinding disk being effected. This adjustment of the grinding disk causes in its turn a lowering of the ground surface, which has the effect to influence the feeler lever 24 in such a manner, that the electric circuit is again interrupted at 33, so that the adjustment of the grinding disk 21 is arrested. The hereinbefore described working cycle is repeated as many times during the progressive movement of the table 22 toward the left, as the wear of the grinding disk causes the contact piece 31 to come in contact with the contact plate 33, so that the longitudinal profile of the ground surface of the blank, that has been passed beneath the grinding wheel is undulated, the height of the undulations corresponding to the difference between the positions of the contact piece 31, at which the latter just closes the circuit and at which it is still able to just interrupt the circuit. This amount is so exceedingly small, that the ground surface may be regarded practically as an even surface. In any case said surface is much more accurate than a surface ground on a machine not provided with means for automatically adjusting the grinding wheel, and it has the further advantage compared with such a surface, that it is exactly parallel to the lower surface of the blank.

The main feature of the embodiment illustrated in Fig. 2 consists in the fact, that the feeler member is not controlled by the ground surface of the blank, but by the working surface of the grinding wheel, for instance the cylindrical surface of the wheel of a circular grinding machine. In such a case the difficulty arises, that the feeler member is actuated by a surface having a very great speed of rotation. The first condition, which has therefore to be fulfilled, is that the feeler member must be made of a material which is harder than the grinding wheel. Such a material is, for instance, diamond. It is, however, advisable, even when diamond is used and is provided with a ground surface, in order to prevent a useless grinding effect of the grinding wheel, to arrange that it does not touch the grinding wheel longer than is absolutely necessary. In a device constructed in the same manner as that shown in Fig. 1, the diamond would, however, constantly touch the grinding wheel, unless an adjustment is just taking place, so that the diamond would also be in contact with the grinding wheel when the latter is running idle, in which case no wear of said wheel takes place and the diamond would thus be subjected to a gradual wear, which has to be prevented as far as possible.

Hence, the device shown in Fig. 2 is constructed in such a manner, that the feeler member touches the working grinding surface only from time to time and for a short

moment, said member serving upon a wear of the grinding disk, to close an electric circuit actuating a relay, which effects a small adjustment of the grinding wheel. At 5 other times the feeler member does not touch the grinding wheel, so that it is not affected by the latter. It will be seen from the following description, that the adjustment, corresponding to the amount of the 10 whole wear, consists in a combination, generally speaking, of a number of single adjustments.

On the shaft 8, which is slowly driven by the pulley 11 and the worm gearing 9, 10, 15 is mounted a sleeve 40 adapted to be moved in the axial direction of said shaft, and a loose sleeve 41 carrying at its upper end a bevel gear 42. The sleeve 40 is provided with clutch teeth 43 and an annular groove 20 44. A pin 45 projects normally into this groove and prevents the teeth 43 from engaging with the teeth 46 of the sleeve 41. The pin 45 carries an adjustable collar 47 25 acted upon by a spring 48, which is arranged between this collar 47 and the bearing 49. The outer end of the pin 45 has a recess 50, into which projects normally a locking lever 51. This lever 51 is pivotally mounted on a fixed pin 52 and is kept in its 30 normal position by a spring 53. A collar 54, having a recess 55 in its periphery, is rigidly connected to the shaft 8. On this collar slides a projection 56 of the feeler lever 24, pivotally mounted on a fixed pin 35 54. One arm of this lever forms a contact lever and carries a contact piece 31, while the other arm is provided with a diamond 26 acting as a feeler. A spring 27 presses 40 constantly the lever 24 on the one hand against the active surface of the grinding wheel 21 and on the other hand against the contact piece 33, so that the projection 56 rests constantly on the cylindrical periphery of the collar 54.

45 As soon as the recess 55 of the collar 54 passes, during the movement of the shaft 8 beneath the pin 56 of the feeler lever 24, the latter is oscillated by the spring 27 both toward the grinding wheel 21 and toward 50 the contact piece 33. If it is assumed, that the contact piece 31 reaches the contact plate 33 before the feeler member 26 comes in contact with the grinding wheel, an electric circuit is closed, so that an electric current 55 flows then from the source 74 through the feeler lever 24 and an electromagnet 57 arranged opposite the locking lever 51. Owing to this, the lever 51 is pulled out of the recess 50 of the pin 45 and the latter is 60 moved out of the annular groove 44 of the sleeve 40 owing to the action of the spring 48. Hence, said sleeve 40 is released and a spring 57 causes the teeth of this sleeve to engage with those of the sleeve 41, so that 65 the rotation of the shaft 8 is now transmit-

ted to sleeve 40 and, by means of the bevel gearing 42, 58, also to the shaft 59. The latter carries at its outer end a disk 60, having an eccentrically mounted pin 61. This pin carries a pawl 62 engaging with a 70 ratchet-wheel 63 and imparting to the latter a feeding movement upon each rotation of the shaft 59. This movement of the ratchet wheel 63 is transmitted to the screw spindle 64, rigidly connected to said wheel, 75 and causes an adjustment of the support 19 of the grinding wheel spindle, and therefore of the grinding wheel 21, toward the feeler 26 of lever 24.

When the clutch sleeve 40 has nearly completed one revolution, a pin 65, fixed to said sleeve is acted upon by a stationary, helical cam surface 66, so that said sleeve 40 is moved longitudinally of the shaft 8, upon further rotation of the latter and is thereby 80 disconnected from the clutch sleeve 41. The rotation of the sleeve 41 and the adjustment of the grinding wheel 21 are then arrested. As soon as the clutch sleeve 40 is returned into its normal position, the rear end of the 85 pin 45 is again pushed into the annular groove 44 of the sleeve 40. This is effected by a cam surface 67 provided on the worm wheel 9 and acting upon a member 68 rigidly connected to the pin 45. Upon the 90 returning of the pin 45 into its normal position, the locking lever 51 is again pressed into the recess 50 by the spring 53, and prevents withdrawal of the bolt 45 from the 95 annular groove of the sleeve 40, after the 100 cam 67 has been moved out of reach of the member 68, as the locking lever 51 is then only acted upon by said spring 53, the electromagnet 57 being no longer energized, since the circuit, closed by the contact piece 105 31 coming in contact with the plate 33, has been immediately interrupted after the recess 55 has been moved out of reach of the projection 56.

Shortly after that the pin 45 has been 110 locked, the recess 55 passes again beneath the projection 56 and the feeler lever 24 is again oscillated toward the contact piece 33 and the grinding wheel respectively. When the grinding wheel has not been moved so 115 near to the feeler member 26, during the preceding adjustment, that the contact piece 31 is prevented from touching the plate 33, the hereinbefore described working cycle is repeated and a second adjusting movement 120 is imparted to the grinding wheel, the amount of this second movement corresponding to that of the first one. This is repeated until an oscillation of the lever 24 finally brings the feeler member into contact with the grinding wheel 21 before the contact piece 31 is able to touch the contact plate 33. In this case the electric circuit is not closed and the electromagnet 57 does 125 not attract the locking lever 51, so that the 130

pin 45 and the clutch sleeve 40 are not released. Thus, the rotation of the shaft 8 is not transmitted to the sleeve 41 and no adjustment of the grinding wheel takes place. 5 Should, however, any wear of the grinding wheel occur, the contact piece 31 is again permitted to touch the contact plate 33 before the feeler touches the grinding wheel and as many small adjustments of said 10 wheel are then again effected as necessary to compensate for the amount of the wear.

Also the sensitiveness of this device depends likewise upon the exceedingly small difference of the positions of the contact 15 piece 31, which are determinative for the closing and the not closing, respectively, of the electric circuit, since the amount of each single adjustment may be made equal to the amount of said difference. The ratio of this 20 amount to the amount of the empirical wear of the grinding wheel determines moreover the duration of the time interval between two successive adjustments and therefore also the number of rotations of the shaft 8. 25 Owing to the very great sensitiveness of this adjusting device with regard to an incorrect position of the active grinding surface, it is difficult to move the grinding wheel by hand at the beginning of the operation exactly into the proper position. In 30 practice an approximation of about 1/10 mm. is the closest, which can be attained. On the other hand, the amount of a single adjustment may be reduced to about 1/1000 35 mm. and the time interval between two adjustments may be extended over about 6 seconds. At the above mentioned distance of the active grinding surface from its proper position, the adjusting device begins, 40 of course, immediately to work. To traverse said distance there are needed, however, if it is assumed that a single adjustment is of the above mentioned amount, 100 adjustments, so that the whole adjustment lasts 45 600 seconds, that is 10 minutes, if it is assumed that a single adjustment lasts 6 seconds. This means an unnecessary loss of time, which is eliminated in the device illustrated in Fig. 3.

50 The device shown in Fig. 3 is a combination of the devices illustrated in Figs. 1 and 2 and it is adapted to be used, for instance, in combination with a machine for grinding toothed wheels having a flat plate-like 55 grinding wheel provided with a narrow circular rim. The part of the device corresponding to that shown in Fig. 1 serves to move the grinding wheel quickly into its proper position at the beginning of the work 60 or after an interchange of the grinding wheels, while the part of the device corresponding to that shown in Fig. 2 serves to effect the adjustment of the grinding wheel in accordance with the amount of the progressive wear taking place during the grind- 65

ing process. Also in this case the provision of a device, corresponding to that shown in Fig. 2 and effecting the work adjustment during the grinding process, is rendered necessary, owing to the circumstance, that the 70 feeler member is not controlled by the blank, but by the grinding wheel, so that, for the purpose of preventing a rapid wear of the feeler member, the same principles are determinative as stated with regard to the device 75 shown in Fig. 2.

The combination of both arrangements requires the following modifications of the mechanism:

Instead of the collar 54 being rigidly 80 connected to the shaft 8 as in Fig. 2, in the arrangement shown in Fig. 3, the collar 54 is adapted to be moved in the axial direction of said shaft. The hub 69 of said collar 54 has an annular groove 70, in which 85 engages a hook 71 on the end of a hand lever 72, the collar 54 being adapted to be moved in such a manner in the axial direction of the shaft 8, by means of said lever 72, that the projection 56 of the feeler lever 24 does not rest any longer on the cylindrical rim of the collar 54. Upon movement of the collar 54 out of reach of the projection 56, the feeler lever 24 is, however, 90 oscillated toward the grinding wheel, which 95 it is prevented from touching owing to the too great distance of said wheel from its proper position, so that the piece 31 comes first into contact with the piece 33. The displacement of the collar 54 has also the 100 effect to connect the electric circuit in such a manner, that upon a closing of said circuit the current does not only flow through the electromagnet 57, but also through the electromagnet 12 fixed to the shaft 59. This 105 magnet carries, in the same manner as the corresponding magnet in Fig. 1, a lever 38, the front end 39 of which engages in the same manner with the teeth of a ratchet wheel 14. Owing to the actuation of the 110 electromagnet 57 the clutch sleeve 40 has been released, in the same manner as in the device of Fig. 2, so that said sleeve engages with the sleeve 41, causing thereby 115 a rotation of the shaft 59. The rotation of this shaft is now transmitted by the electromagnet 12 and the lever 38 to the ratchet wheel 14, loosely mounted on said shaft and to the small spur gear 15 rigidly 120 connected to said wheel 14. The gear 15 engages in its turn with a spur gear 16, rigidly connected to the ratchet wheel 63. While the electromagnet 12 is energized, the revolving bevel gear 42 causes a much 125 quicker adjustment of the grinding wheel by means of the spur gears 15, 16, than that caused by the pawl and the ratchet gear 62, 63. Rotation of the shaft 59 is stopped as soon as the pin 65, acted upon by the helical surface 66, moves the sleeve 40 out 130

of engagement with the sleeve 41, but it is restarted upon release of the member 68 from the cam 67, as the electromagnet 57 is still being energized, so that the pin 45 5 is not locked. The quick adjustment of the grinding wheel, by means of the members 12, 38, 14, 15, 16, occurs at short intervals until the active surface of the grinding wheel touches the feeler member. As soon 10 as this is the case, the circuit is interrupted at 33 and the magnet 12 is rendered inoperative. The spring 34 then causes the lever 38 to disengage the ratchet wheel and the gearing 15, 16 is again arrested. Only 15 the shaft 59 is further rotated until the sleeve 40 is caused to disengage the sleeve 41. But, since the electromagnet 57 is also no longer operative, the lever 45 is locked immediately afterward, so that any adjusting 20 movement of the grinding wheel is interrupted.

When the pawl 62 has been moved away from the wheel 63 before the starting of said quick adjustment, the rotation imparted to the shaft 59 for a short moment after said quick adjustment has been effected, does not cause any further adjustment of the grinding wheel, so that the latter is moved exactly into its proper position owing 25 to said quick adjustment. As soon as this is the case, the collar 54 is brought back within reach of the projection 56 of the feeler lever 24 by means of the hand lever 72, the inclined surface 73 on the collar 54 30 causing said pin to ride up onto the cylindrical rim of said collar. At the same time the pawl 62 is moved back into its working position. Now when the grinding wheel begins 35 to wear, this device works just in the same manner as that shown in Fig. 2, since the electromagnet 12 has been disconnected from the electric circuit owing to the displacement imparted to the hand lever 72.

Both in Fig. 2 and in Fig. 3, it has been 40 assumed, that the support for the grinding wheel and the whole adjusting device are mounted as in Fig. 1, on a common slide, which is adapted to be adjusted in any suitable manner by hand or by the machine 45 itself, without said adjusting device being affected in any way. In this manner it is possible to determine the position of the active grinding wheel according to requirements, while the adjusting device is only 50 operated by those displacements of the active grinding surface, which are due to the wear of the grinding wheel. To this end it is particularly advisable to provide a special slide for the support for the grinding 55 wheel, which is adapted to be displaced relatively to the adjusting device. In this case the position of the active grinding surface relatively to the adjusting apparatus 60 is then always determined by the position 65 of the contact piece 33 on the one hand and

the positions of the contact piece 31 and the feeler member 26 on the other hand.

Upon comparison of Fig. 1 on the one hand and Figs. 2 and 3 on the other hand it will be seen that, in Figs. 2 and 3, the 70 feeler lever acts at the same time as a contact lever, while in Fig. 1 the feeler lever and the contact lever form two separate pieces. In this latter case I always prefer to provide two levers, as a single lever 75 might easily be bent. Let it be assumed, for instance, that the device of Fig. 1 comprises only the lever 24. In this case the contact piece 31 would have to be fixed to the left hand end of this lever 24 in a downward direction and the contact piece 33 would then have to be arranged opposite and below said piece 31. If an elevated work surface should now be moved under the feeler lever, while the grinding wheel is also too much 80 elevated, said lever could not be oscillated and it would thus be bent. The feeler lever would also be prevented from following the undulations of the ground surface, so that the progressively higher work surface would 85 also cause a bending of said lever, as the latter would be already in contact with the small contact plate for the purpose of starting the adjustment of the grinding wheel, while the effect of the adjustment can only 90 influence the feeler, when the work surface, ground again to the proper height, passes beneath the feeler member. This difficulty is overcome by providing two levers instead of only one, as the feeler lever 24 is then 100 able to follow each rising of the grinding wheel, the left hand end of said lever being in this case even able to oscillate, when the contact lever 29 is already prevented from oscillating by the contact piece 31 resting 105 on the small contact plate 33.

In the arrangements shown in Figs. 2 and 3, such a division of the lever in two single parts is not necessary, as the contact lever can never be bent when the grinding wheel 110 is in a wrong position.

This difference in the arrangement of the feeler lever and the contact lever, due to the above mentioned reasons, in the two embodiments is, however, practically of no importance for the action of the feeler lever as a switch. It is only essential, that the oscillation of the feeler lever be able to effect a closing and opening of the electric circuit, it being immaterial, whether this is accomplished directly, as in Figs. 2 and 3, or in an indirect manner, as in Fig. 1.

It has been mentioned, that the device shown in Fig. 1 is particularly adapted to be used in connection with a surface grinding machine having a cylindrical wheel, while the embodiments shown in Figs. 2 and 3 are more adapted to be used in connection with circular grinding machines and machines for grinding toothed wheels 125 respectively.

tively. Of course, the devices shown in Figs. 2 and 3 may also be used in connection with surface grinding machines of the type shown in Fig. 1, that is, where the feeler lever is controlled by the blank and not by the grinding wheel, it being, however, understood, that in this case the arrangement of the feeler lever and contact lever would remain the same as in Fig. 1, owing to the above stated difficulties. On the other hand, it would also be possible to use the device shown in Fig. 1 in connection with circular grinding machines and to control the feeler by the blank instead of by the grinding wheel. Also in this case it would be necessary to provide a separate feeler lever and contact lever respectively, as this division of the feeler and contact lever into two parts is only necessary when the feeler is controlled by the blank, while when the grinding wheel is the controlling agent, the feeler lever and contact lever may be formed in one piece.

With regard to the device shown in Fig. 1, it has been assumed, that the blank is moved in such a direction relatively to the grinding wheel, that the feeler lever comes in contact with the surface, which has just been ground by the grinding wheel during the movement of the blank beneath said wheel. In other words, it has been assumed that the blank is moved relatively to the grinding wheel, and that the axis of the grinding spindle does not change its position. In this case the feeler lever is able to react when a wear of the grinding wheel takes place and to effect in the described manner a corresponding adjustment of the grinding wheel by means of the device shown in Fig. 1. The conditions are, however, quite different when the table 22 is moved in the opposite direction. The feeler lever is then moved a second time, but in the opposite direction, over the blank surface, which has been ground and by which it has been controlled during the previous travel of the table 22, and it is prevented from coming in contact with the surface, which is ground during this travel of the table. Owing to this, the device is not able to compensate the wear of the grinding wheel taking place during the return travel by imparting a corresponding adjusting movement to said wheel. This lever may even cause entirely wrong adjustments, when the feeler is not removed from the blank during the return travel of the table, or when the electric circuit is not interrupted. Thus, the device shown in Fig. 1 works only in a proper manner for one direction of movement of the table, that is, for the direction assumed in the hereinbefore description to be the direction of movement of the table 22, and it can only be used in connection with machines, which grind when the

table carrying the blank is moving in both directions, by the provision of a feeler lever, and a contact lever respectively on each side of the grinding wheel 21.

Fig. 4 illustrates such a double arrangement of the levers and the modifications, which have to be applied in this case to an arrangement of the kind shown in Fig. 1.

The circuit of the electromagnet 12 comprises a control lever 78 acted upon by the dogs 75 and 76 and pivotally mounted on the pin 77 and reversing the direction of movement of the table 22. In one end position of this table 22 the control lever 78 is acted upon by the dog 76, so that its end 79 comes in contact with the small contact piece 80. The electric current, acting upon the electromagnet 12, flows therefore through the contact piece 31^a of the contact lever 29^a and the small contact plate 33^a. Upon a reversal of the control lever 78 the direction of movement of the table 22 is reversed also, so that the table is now moving in the direction of the arrow 81. The feeler lever 24^a comes thus in contact with the surface, which is ground during this movement of the table 22, and as the corresponding contact lever 29^a is connected to the electric circuit, the adjusting device is able to fulfil the task, which has been assigned to it, that is, to compensate the wear of the grinding wheel by means of a corresponding adjustment of said wheel. During this movement of the table 22 in the direction of the arrow 81, the feeler lever 24 and contact lever 29, which are arranged on the other side of the grinding wheel 21, are not operatively connected to the adjusting device, so that the movement of the feeler lever 24 does not influence the device. In the other end position of the table 22 the control lever 78 is reversed by the dog 75, so that its end 79 comes to rest on the small contact piece 82. The current, energizing the electromagnet, flows then through the contact piece 31 of the contact lever 29 and the small contact plate 33. The double lever 29, 24 is now electrically connected to the adjusting device, while the double lever 29^a, 24^a is disconnected therefrom. As also the direction of movement of the table 22 has been reversed, so that it is moving in the opposite direction to the arrow 81, the feeler lever 24, controlling now the adjusting device, is able to come again in contact with the surface, which is ground during this movement of the table, and the device is thus able to effect, also for this direction of movement of the table, an adjustment corresponding to the wear of the grinding wheel. Of course, the levers of the two systems have to be set in such a manner, that both contact levers close the electric circuit, when their corresponding feeler levers come in contact with one and the

same surface. This adjustment of the levers may be effected in a very simple manner by adjusting the contact pieces 31 and 31^a respectively, they being formed in the shape of set-screws.

Thus, the device of Fig. 1 is rendered capable, by duplicating the lever arrangement and the electric connections according to Fig. 4, of adjusting the grinding wheel in accordance with its wear for both directions of movement of the table carrying the blank.

Hereinbefore it has always been assumed, that the adjustment of the grinding wheel is started upon the overcoming of a spring action by the pulling action generated at the moment in which the electric circuit is closed by the contact lever. The arrangement may, however, be also such, that the adjustment is not effected by the closing of an electric circuit, but by the opening of such a circuit. In such a case, the spring and the electromagnet change their roles. Thus, in the arrangements shown for instance in Figs. 2 and 3, the electromagnet 57 has to take the place of the spring 53 and fulfil the task of the latter, while on the other hand the spring 53 has to fulfil the function of the electromagnet 57. The pulling action of the electromagnet overcomes then the spring action at the time, during which the device is not operative, while this spring action overcomes said pulling action at the time, during which the adjustment of the grinding wheel is effected. Further, it is also only essential for these devices that the feeler lever act either directly, as in the device according to Figs. 2 and 3, or indirectly, as in the device according to Fig. 1, as a switch in an electric circuit, which causes, upon its closing or opening, the adjustment of the grinding wheel.

Furthermore, it has hereinbefore always been assumed, that the adjustment of the grinding wheel is effected upon the coupling of a constantly rotating shaft 8 to the elements which effect the adjustment. This is, however, not essential, as the elements effecting the adjustment might as well be actuated by a small electromotor, which normally would not be running and which would only be set in motion upon the closing of the electric circuit by the contact lever, such motor effecting thereby the adjustment either in one operation, as in the arrangement shown in Fig. 1, or in an intermittent manner, as in the arrangements shown in Figs. 2 and 3.

For the proper working of the device it is also not essential, that the compensation for the wear of the grinding wheel be effected by the adjustment of the grinding wheel, for said compensation might as well be effected by a corresponding adjust-

ment of the work. In this case the whole device, comprising the feeler members, contact and adjusting-members, has only to be arranged on the table of the machine and not on the support for the grinding wheel. 70 Such an arrangement is particularly adapted to be applied to machines, in which also the ordinary feed movement is controlled by the blank, as the adjusting members may then act directly upon the feeding member, 75 so that no special slide, adapted to be moved relatively to the adjusting device, has to be provided, as it is the case in the arrangements shown in Figs. 1 to 3.

What I claim is:

1. In a grinding machine, the combination with the work-support, the grinding-wheel, and means for feeding one relative to the other, of means for automatically compensating for the wear of the grinding-wheel, comprising a constantly driven shaft, a clutch to connect the same to said feeding means, and electro-magnetic means to control said clutch, the circuit of said electro-magnetic means including a feeler responsive to wear of said grinding-wheel. 80

2. In a grinding machine, the combination with the work-support, the grinding-wheel, and means for feeding one relative to the other, of means for automatically compensating for the wear of the grinding-wheel, comprising a constantly driven member, means to connect the same to said feeding means, a feeler, the position of which is determined by the wear of the grinding-wheel, and means, controlled by said feeler, to render said connecting means operative whenever the grinding-wheel has worn a certain amount. 95

3. In a grinding machine, the combination with the work-support, the grinding-wheel, and means for feeding one relative to the other, of means for automatically compensating for the wear of the grinding-wheel, comprising a feeler lever, the position of which is determined by the wear of the grinding-wheel, an electric circuit arranged to be opened or closed by said feeler lever, a source of power, a clutch to connect the latter to said feeding means, an electromagnet in said circuit controlling the operation of said clutch, and means to disengage said clutch when said circuit is opened. 105

4. In a grinding machine, the combination with the work-support, the grinding-wheel, and means for feeding one relative to the other, of means for automatically compensating for the wear of the grinding-wheel, comprising a feeler lever, the position of which is determined by the wear of the grinding-wheel, an electric circuit arranged to be opened and closed by said feeler lever, a constantly rotating member arranged to oscillate said lever at regular in- 110 115 120 125 130

8
5 intervals, means, controlled by said circuit to intermittently connect said member to said feeding means, and means, also controlled by said circuit, to connect said member to said feeding means to impart a relatively rapid and greater feeding movement between the grinding-wheel and work.

10 5. In a grinding machine, the combination with the work-support, the grinding-wheel, and means for feeding one relative to the other, of means for automatically compensating for the wear of the grinding-wheel, comprising a feeler lever, the position of which is determined by the wear of 15 the grinding-wheel, an electric circuit arranged to be opened and closed by said feeler lever, a constantly rotating member arranged to oscillate said lever at regular intervals, means, controlled by said circuit to intermittently connect said member to said feeding means, means, also controlled by said circuit, to connect said member to said

feeding means to impart a relatively rapid and greater feeding movement between the grinding-wheel and work, and manually-operable means to move said rotating member so that it no longer oscillates said lever, said manually-operable means at the same time affecting said circuit so as to render operative the said means for imparting the rapid feeding movement.

15 6. A feeler member adapted to be used in devices for automatically compensating the wear of grinding wheels occurring during the grinding operation, comprising a diamond having a ground flat surface, substantially as described.

20 In testimony that I claim the foregoing as my invention, I have signed my name in presence of two subscribing witnesses. 40
